UNITED STATES PATENT OFFICE.

JOHN MORRISON, OF TROY, NEW YORK.

BRUSH.

Application filed March 7, 1921. Serial No. 450,222.

To all whom it may concern:

Be it known that I, JOHN MORRISON, a citizen of the United States, residing at Troy, in the county of Rensselaer and State of New York, have invented new and useful Improvements in Brushes, of which the following is a specification.

Reference may be had to the accompanying drawings, and the reference characters 10 marked thereon, which form a part of this specification. Similar characters refer to similar parts in the several figures therein.

This invention relates more particularly to the manufacture of brushes in which the 15 knots of bristles are mounted upon or in a supporting pad or block which is enclosed within a casing or shell of sheet material with the bristles projecting through apertures in one wall of the casing.

20 Certain features of the invention relate to the manufacture of a reinforced supporting back for various toilet articles, particularly toilet brushes.

The principal objects of the invention are 25 to facilitate and reduce the cost of manufacture and to give greater solidity to the back of the article.

Other objects will appear in connection with the following description.

30 Fig. 1 of the drawings is a plan view of the open side of a hollow brush-back-shell made of sheet material.

Fig. 2 is a similar view of a cup-shaped liner also formed of sheet material adapted 35 to be inserted within the head portion of the shell shown in Fig. 1 to reinforce the same.

Fig. 3 is a similar view of a filling-block adapted to be inserted within the handle portion of the shell shown in Fig. 1, to reinforce 40 the same.

Fig. 4 is a similar view showing the cup-shaped liner and the reinforcing block inserted within the shell of the back.

Fig. 5 is a central longitudinal section of 45 the shell of the back taken on the broken line 5-5 in Fig. 1.

Fig. 6 is a similar view of the cup-shaped liner taken on the broken line 6-6 in Fig. 2.

Fig. 7 is a similar view of the handle-reinforcing block taken on the broken line 7-7 in Fig. 3.

Fig. 8 is a similar sectional view illustrating the manner of assembling the cup-shaped liner and handle-reinforcing block 55 within the shell of the back.

Fig. 9 is a similar view showing the face-plate attached to the shell of the back with the brush-supporting pad enclosed within the head portion of the casing thus formed.

Fig. 10 is a similar view of a broken-away 60 portion of the handle of the brush thus formed.

Fig. 11 is a plan view of the back of the face-plate with the bristle-supporting pad mounted thereon before the face-plate is attached to the shell of the back.

Fig. 12 is a side view of the same.

Fig. 13 is a plan view of a broken-away portion of the face-plate before the pad has been formed thereupon.

Fig. 14 is a view in vertical longitudinal section taken on the broken line 14-14 in Fig. 11, showing the face-plate and bristle supporting pad in position in the mold whereby the pad is formed upon the face- 75 plate.

Referring to the drawings wherein the invention is shown in preferred form, 1 is the head-portion, and 2 the handle-portion of an integral back-and-handle shell adapted for 80 use in the manufacture of a handled toilet article, such as a hair-brush, in accordance with my invention.

This shell can be made of any suitable thin or sheet material, and is preferably 85 made of sheet celluloid molded to the desired form.

A cup-shaped liner, 3, made of similar sheet material, preferably celluloid, is adapted to fit more or less loosely within the head 90 portion, 1, of the shell.

A filling block, 4, is adapted to fit more or less loosely within the handle portion, 2, of the shell, the filling-block being complementary to the liner to approximately fill the 95 shell.

The filling-block, 4, may be made of wood or other material having the necessary strength and rigidity to form a substantial support or reinforce for the handle portion 100 of the brush.

In seating the liner, 3, and filling-block, 4, in the shell, I first place within the shell, in plastic condition a hardenable plastic material, 15, which will flow under pressure, 105 and then insert within the head portion of the shell the cup-shaped filler, 3, and within the handle portion of the shell, the filling-block, 4, as shown in Fig. 4. I then seat the liner and filling-block within the shell by 110

pressure applied to the exposed edge of the liner and exposed face of the filling-block by means of a presser plate, 5, applied to the open side of the shell while the back or closed side of the shell rests upon a support or table, 6.

- Pressure is thus applied to the liner and the filling-block until the edge of the liner and the face of the filling-block are flush
- 10 with the edge of the shell, and the parts are maintained in this position until the plastic material hardens so that the space between the shell and the liner and the filling-block is filled with the hardened plastic material.
- 15 Various kinds of hardenable plastic material may be employed for this purpose, an example being paraffin which when heated is sufficiently plastic for the purpose and at normal temperatures is sufficiently hard to
- 20 form a solid body between the shell and the liner and the filling-block.

After the liner and filling-block have been thus seated within the shell, a face-plate, 7, is secured to the shell covering the filling-block and the liner as shown in Fig. 9.

For certain purposes of the invention, the face-plate may be secured to the shell in any known manner; but I prefer, particularly if the shell and face-plate are made

30 of celluloid, to secure the face-plate to the edge of the shell by celluloid cement.

I also prefer to secure the face-plate to the edge of the liner in the same manner, and for this purpose it is desirable that

35 the edge of the liner should be flush with the edge of the face-plate.

After the face-plate has been secured to the shell any edge portions of the face-plate which project outwardly beyond the shell

40 are removed and the cemented joint is effectively concealed by buffing.

In carrying out my invention with respect to a brush the head portion of the face-plate is formed with perforations, 8, each adapted to receive a small knot or bunch of bristles, 9, and I mount upon the face-plate a bristle-supporting pad, 10, from which the bristles, 9, project through the perforations, 8, in the face-plate.

50 The face-plate may be provided in any known manner with such a bristle-supporting pad mounted thereon.

In Fig. 14, I have shown a mold apparatus adapted for forming such a bristle-supporting pad upon the face-plate. The face-plate is placed upon the lower mold member, 11, with its perforations, 8, registering with corresponding openings, 12, in the mold member, 11, and bristles are inserted through

60 the perforations, 8, into the respective openings, 12, leaving the ends of the bristles exposed above the surface of the face-plate, 7.

Hardenable plastic material or composition, 10^a, is then applied to the exposed

65 ends of the bristles around and upon which

it is molded by the upper mold member, 14. When the composition, 10^a, has hardened sufficiently it becomes the pad, 10.

The upper mold member, 14, is removed and the face-plate, 7, is removed from the lower mold member, 11, taking with it the pad and pad-supported bristles. The face-plate is then cemented to the shell in the manner above described with the pad enclosed and secured between the face-plate 75 and the liner as shown in Fig. 9.

In carrying out the invention with respect to articles other than brushes or with other kinds of brushes, the face-plate may be formed with one or more openings of a form 80 and size adapted for the desired purpose.

If the handle for the article is not desired, the handle portion of the shell and face-plate and the filling-block may be dispensed with, in which case the shell would be 85 formed to fit entirely around the circumference of the liner.

In making brushes in accordance with my invention I preferably make the shell or casing of celluloid or similar material containing pyroxylin, and by employing paraffin or other wax-like substance free from pyroxylin-solvent I am able to mount the liner within the back-shell in substantially solid relation thereto, thereby giving to the combined back-shell and liner a permanent form which cannot be obtained by the use of filling substances containing pyroxylin-solvent.

What I claim as new and desire to secure by Letters Patent is—

1. A toilet article having a black-shell containing pyroxylin, a cup-shaped liner seated within the shell, the space between the liner and shell being filled with hardened plastic material free from pyroxylin-solvent, and a face-plate secured to the shell covering the edge of the liner.

2. A toilet article having integral back-and-handle-shell, a cup-shaped liner seated within the head portion, and a complementary filling-block separated from said liner seated within the handle portion, of the shell, the space between the shell and the liner and the filling-block being filled with hardened plastic material, and a face-plate secured to the shell covering the filling-block and the edge of the liner.

3. A brush having a back-shell containing pyroxylin, a cup-shaped liner seated within the shell, the space between the liner and shell being filled with hardened plastic material free from pyroxylin-solvent, a perforated face-plate secured to the shell covering the liner, and a bristle-supporting body 125 secured between the face-plate and the liner with bristles projecting from said body through the perforations in the face-plate.

4. A brush having an integral back-and-handle-shell, a cup-shaped liner seated with-

in the head portion, and a separate complementary filling block seated within the handle portion, of the shell, the space between the shell and the liner and handle-block being filled with hardened plastic material, a perforated face-plate secured to the shell covering the filling-block and liner, and a bristle-supporting body secured between the liner and the face-plate with bristles projecting from said body through the perforations in the face-plate.

5 5. A brush having a back-shell of sheet material containing pyroxylin, a cup-shaped liner seated within the back-shell with its 10 edge flush with the edge of the shell, the space between the liner and shell being filled with hardened plastic material free from pyroxylin-solvent, a perforated celluloid

face-plate secured to the flush edges of the shell and liner covering the liner, and a 20 bristle-supporting body secured between the face-plate and liner with bristles projecting from said body through the perforations in the face-plate.

6. A toilet-article having a back-shell, a 25 cup-shaped liner seated within the shell with its edge terminating flush with the edge of the shell, the space between the liner and shell being filled with hardened plastic material, and a face-plate secured to the flush 30 edges of the liner and shell covering the edge of the liner.

In testimony whereof, I have hereunto set my hand this 18th day of February, 1921.

JOHN MORRISON.
